UNITED STATES PATENT OFFICE.

EMMOR M. MALLETTÉ, OF CHICAGO, ILLINOIS.

SHARPENING DEVICE.

1,025,412.

Specification of Letters Patent.

Patented May 7, 1912.

Application filed May 10, 1911. Serial No. 626,348.

To all whom it may concern:

Be it known that I, EMMOR M. MALLETTÉ, a citizen of the United States, residing at Chicago, in the county of Cook and State 5 of Illinois, have invented certain new and useful Improvements in Sharpening Devices, of which the following is a specification.

My present invention relates to sharpening devices especially adapted for household use, and of that character embodying adjustable metal cutting disks supported by means which form guides through which knives and other implements may be moved 15 against the cutting disk and sharpened.

The object of my invention is to provide a neat and practical sharpener which may be fastened to any suitable support and adapted to various sizes and characters of 20 implements that require sharpening.

Another object of my invention is to provide a device in which the parts are so arranged as to produce a long bevel upon the implement, resulting in a thin sharp 25 edge.

With these and other objects which will be made apparent, my invention resides in the features of construction and arrangement to be hereinafter described with reference to the accompanying drawings, in 30 which—

Figure 1 is a perspective view of my improved device, secured in operative position, and Fig. 2 is a rear elevation thereof, 35 slightly enlarged. Fig. 3 is a plan view of the sharpening disk, detached.

Referring now to these figures, my improved device comprises a supporting member which consists of a wire bent to form 40 spaced and substantially parallel extensions 5, between which a headed fastening member, such as a screw 6 as shown in Fig. 1, may be extended into a suitable support. The extremities 6^a of this wire support are 45 bent to upstand and slightly diverge from one another.

The holding plate 7 is provided with lower side wings 8 which, as shown, are bent inwardly to extend around the upstanding supporting wire portions 6^a, and to thus hold said plate in position. This plate is further provided with an indented central portion 9 similar in shape to the hardened metal cutting disk 10, which I preferably 55 form polygonal with a plurality of straight sides, as shown in the drawing, for a pur-

pose to be hereinafter described. This disk 10 is adapted to be placed in the indented portion 9 of the holding plate 7, and when in such position, as particularly shown in Fig. 1, its extreme side portions extend beneath the upstanding supporting wire portions 6^a, which coöperate with the holding plate to adjustably and removably hold the disk in position. The holding plate 7 is also provided with upper side wings 11 which are flared or bent in a direction opposite to that of the lower wings 8 and which coöperate with the upper ends of the upstanding supporting wire portions 6^a to form guides 70 between which the blade to be sharpened may be moved against the contiguous straight edge of the sharpening disk, and formed with a long bevel in order that it may be given a very sharp edge. The holding plate 7 is also provided with an upper central cut-out portion 12, the base 13 of which extends slightly below the corresponding straight edge of the sharpening disk 10, and the sides of which cut-out portion form guides for the blades of scissors or other instruments, the edges of which have only very slight bevels.

Fig. 1 shows the device in position ready for operation, and when in such position 85 it is only necessary to slightly flex the holding plate 7, in order that the cutting disk 10 may be removed and readjusted so that selected ones of its straight sides may be brought into position opposite the several 90 guides, or that a new disk may be substituted.

I claim:

1. The combination of a supporting member having upstanding portions, a holding 95 plate having means to engage said upstanding portions, and a polygonal sharpening disk supported upon one surface of said plate, and having its side portions extending between the plate and said upstanding portions of said support, said disk being removable for readjustment to place selected ones of its sides in operative position.

2. The combination of a supporting member having upstanding portions, a holding 105 plate having means to engage said upstanding portions and provided with guides, and a sharpening disk supported upon one surface of said plate, having its side portions 110 extending between the plate and said upstanding portions of said support, said sharpening disk being polygonal and being

removable for readjustment to present selected ones of its sides opposite the said blade guides.

3. The combination of a supporting member having upstanding portions, a polygonal sharpening disk, a holding plate having means to engage said upstanding portions of said support, and coöperate with said upstanding portions of said support to clasp 10 the said sharpening disk therebetween, said holding plate having guides and being provided with portions which also coöperate with said upstanding portions of said support, to form other guides.
- 15 4. The combination of a supporting member comprising a wire bent to form spaced extensions adapted to be secured to a suitable support, and having its extremities bent to upstand, a holding plate having lower

side wings bent inwardly about the lower 20 portions of said upstanding extremities, and provided with upper side wings bent in an opposite direction, said holding plate being also provided with an upper cut-out portion, the sides of which form guides, and having 25 a central indented portion, the sides of which extend beneath the upstanding wire extremities, and a polygonal sharpening disk disposed within said centrally indented portion of said holding plate, and removable 30 for readjustment to place a new working portion in operative position.

In testimony whereof I affix my signature in presence of two witnesses.

EMMOR M. MALLETTÉ.
